UNITED STATES PATENT OFFICE.

FRETS THEDSEN, OF DIKE, IOWA.

ROCKING-CHAIR ATTACHMENT.

1,163,486.

Specification of Letters Patent.

Patented Dec. 7, 1915.

Application filed July 30, 1914. Serial No. 854,153.

To all whom it may concern:

Be it known that I, FRETS THEDSEN, a citizen of the United States, residing at Dike, in the county of Grundy and State of Iowa, have invented certain new and useful Improvements in Rocking-Chair Attachments, of which the following is a specification.

This invention appertains to rocking chair attachments for automatically supplying a practically constant current of air for the occupant of said chair during rocking movement, and my main object is to provide simple manipulating means whereby the air supplying member or members may be rendered operative and inoperative at will when the chair is used. To this end I employ a pair of bellows attached to the chair and having air discharging conduits arranged to direct the air against the occupant of the chair, in combination with locking members adapted to engage the bellows upon manipulation of an operating member so as to hold each bellows element compressed and inoperative when the air supply is not desired.

A further object in view is to provide adjustable connections intermediate the attachment and the chair structure so as to enable the invention to be connected to various types or sizes of rocking chairs.

These and such other objects as may hereinafter appear are attained by the novel construction, combination and arrangement of parts to be hereinafter specifically described and claimed.

Reference will now be had to the accompanying drawings forming a part of this specification, wherein:

Figure 1 is a perspective view of a rocking chair with my attachment applied thereto. Fig. 2 is a horizontal sectional view taken on a plane beneath the chair seat and showing the attachment in plan. Fig. 3 is a vertical sectional view on the line 3—3 of Fig. 2 through my attachment. Fig. 4 is a perspective view of the attachment and showing more clearly the bellows members locked in inoperative position. Fig. 5 is a detail sectional view on the line 5—5 of Fig. 2 and showing the adjustable connection intermediate the attachment and the chair. Fig. 6 is a similar view to Fig. 5 but taken

on a line 6—6 of Fig. 2 at right angles to the view of said figure.

Describing the embodiment of my invention and referring to the drawings, the numeral 1 designates a rocking chair of conventional type beneath the seat of which my attachment is adapted to be secured. As chairs of this character vary in size and particularly with reference to the width at the front and rear portions, it is desirable to employ adjustable attaching means intermediate the attachment hereinafter to be more particularly described and the chair structure. This means consists of angular shaped brackets 2 one of which is secured to each leg by screws or other fastening members 3 passing through one arm of said bracket, the other or horizontal arm of the bracket 20 projecting inwardly and extending through a keeper 4 secured in any desired manner to the main plate or board 5 of a double bellows. The keeper 4 is provided with a set screw 6 which is provided to hold the last 75 mentioned arm of the bracket 2 in fixed relation to the bellows. The same attaching arrangement is provided for each bracket 2 and it will be obvious particularly by reference to Fig. 2 that the bellows attachment 80 may be centralized between the legs of the rocker by this arrangement and considerable latitude is allowed for chairs of different widths and different sizes. As inferred from the foregoing, the bellows consist of 85 two compartments 7, 7' and the movable plates 8 and 8' are employed to supply air during rocking movement of the chair, and which air is drawn through the inlet conduits 9, 9' extending through the main plate 90 5 and into the respective air chambers 7 and 7'. Each inlet opening has a flap valve 10 so as to effectively close this passage when the air is being forced out through the discharge conduits 11, 11'. The last mentioned conduits pass preferably outwardly of the chair and vertically to a point adjacent to the position occupied by the head of the occupant of the chair and I preferably provide the terminal of each conduit with a spray nozzle 100 12 to most effectively deliver the air against the face of the occupant of the chair.

As will be noted by reference to Fig. 3,

each of the movable plates 8 and 8' hingedly connected to the central block 13 at 14 is provided with a roller or caster member 15 at its lower edge, which caster rests upon 5 the surface of the floor beneath the chair and is maintained normally in contact therewith by means of the spring 16 secured at its opposite ends to the respective movable bellows plates 8 and 8'.

10 With the foregoing description in view it will be clearly understood that as the chair is rocked to and fro the pair of bellows of this attachment will keep a substantially constant stream of air flowing through the 15 discharge conduits. When it is cool it is desirable that the bellows attachment be rendered inoperative and for this purpose I employ locking members adapted to coact with the bellows to hold them compressed to a 20 position such as shown most clearly in Fig. 4. To this end I secure an overhanging bracket 17 at each end of the main bellows plate 5 and pivotally mount on said brackets the locking members 18, 19, said locking members 25 being connected to a common operating rod 20 at opposite ends of the latter. It will be observed that the rod 20 is connected to the member 18 at a point above its pivotal connection with the bracket 17 while its connection with the locking member 19 is below the pivotal connection of this member to its corresponding bracket 17. Furthermore the locking member 19 is provided with a slot so that the connection 20' of the rod 20 30 is shiftable upwardly and downwardly in said member, the rod 20 being provided intermediate its length with a pair of notches 21 which are adapted to engage with an angular catch plate 22 secured to the upper 35 surface of the bellows board 5.

40 In explanation of the locking mechanism, it will be understood that when it is desired to render the bellows inoperative the occupant or operator of the chair rocks said 45 chair rearwardly so as to compress the rear bellows element and raising the forward movable bellows plate 8'. The catch members 18 and 19 may be simultaneously engaged with the respective movable plates 8 and 8' by shifting the operating rod 20 in a rearward direction, first raising said rod upwardly to disengage the rearmost notch thereon. A downward movement of the rod will engage the other notch 21 with the plate 22 and maintain the locking catches 18 and 19 engaged with the bellows which are thereby held in compressed or inoperative position and the chair may then be used as the ordinary rocking chair.

50 Having thus described the invention, what is claimed as new is:—

1. In combination, a rocking chair, a bellows connected thereto and coacting with the surface on which the chair is disposed

for supplying air during rocking motion of 65 said chair, discharge means for directing the air against the occupant of the chair, locking means, manipulative means adapted to engage and disengage the locking means with the bellows to render the same operative and inoperative during rocking motion, and locking means co-operating with the manipulative means to hold the bellows locking means in adjusted engaged and disengaged positions. 75

2. In combination, a rocking chair, a bellows connected thereto, means maintaining the bellows coacting with the surface on which the chair is disposed during rocking motion of the same, locking means for engaging the bellows to hold the same away from the surface whereby to render the bellows inoperative, a manipulating means for operating said locking means and having shiftable connection therewith, and means 80 co-operating with the manipulating rod whereby to hold the locking means in engaging position with respect to the bellows. 85

3. In combination, a rocking chair attachment comprising a pair of bellows secured beneath the chair and adapted to normally coact with the surface on which the chair is disposed for actuating said bellows, catch members co-operating with the bellows and adapted to hold the bellows compressed and 95 inoperative with respect to the surface aforesaid, and manipulative means common to said catch members for simultaneously engaging the catch members with their respective bellows. 100

4. In combination, a rocking chair attachment comprising a pair of bellows secured beneath the chair and adapted to normally coact with the surface on which the chair is disposed for actuating said bellows, a catch member pivotally mounted adjacent each bellows and adapted to hold the bellows compressed and inoperative with respect to the surface aforesaid, a connecting rod connected to one of said catch members at one 110 side of its pivot and to the other catch member at the opposite side of its pivot to that of the first mentioned catch member, and locking means co-operating with the rod to hold the catch members engaged or disengaged from the bellows. 115

5. In combination, a rocking chair attachment comprising a pair of bellows secured beneath the chair and adapted to normally coact with the surface on which the chair 120 is disposed for actuating said bellows, a catch member pivotally mounted adjacent each bellows and adapted to hold the bellows compressed and inoperative with respect to the surface aforesaid, a connecting rod connected to one of said catch members at one side of its pivot and to the other catch member at the opposite side of its pivot to that 125

of the first mentioned catch member, one of said catch members being slotted and the connection intermediate the connecting rod aforesaid being movable in said slot, and locking means comprising a catch plate secured to the bellows and adapted for engagement with the connecting rod upon shifting of the same whereby to hold the

catch members engaged or disengaged from the bellows.

In testimony whereof I affix my signature in presence of two witnesses.

FRETS THEDSEN.
